UNITED STATES PATENT OFFICE.

EDWIN R. CAHOONE, GEORGE WALKER, AND CHARLES E. CAHOONE, OF NEWARK, NEW JERSEY; SAID CHAS. E. CAHOONE AND GEORGE WALKER ASSIGNORS TO SAID EDWIN R. CAHOONE.

APPLICATION OF VARNISHES.

SPECIFICATION forming part of Letters Patent No. 242,507, dated June 7, 1881.

Application filed November 19, 1880. (Specimens.)

To all whom it may concern:

Be it known that we, EDWIN R. CAHOONE, GEORGE WALKER, and CHARLES E. CAHOONE, all of Newark, in the county of Essex and State of New Jersey, have invented a new and useful Improvement in the Mode of Applying Japan and other Varnishes; and we do hereby declare that the following is a full and complete description thereof.

10 Our invention is applicable to all japan or other body varnishes.

Heretofore body-varnishes, being in fluid form, have been applied in successive coats or layers until the required thickness or body has 15 been attained, a sufficient time being permitted to intervene between the successive applications to let the preceding one become thoroughly dried or baked. In the case of fine wood-work from eight to twelve coats of copal 20 varnish are required. For metal with japan two or more coats are required.

Great care must be exercised to exclude dust from the varnish-room, and large spaces are required by reason of the long time required 25 for the finishing of any single piece.

Metallic articles coated with japan are subjected to heat in an oven to facilitate the drying and to impart extra hardness to the varnish. Wood coated with body-varnish of any 30 kind may be subjected to heat for the same purpose.

The numerous manipulations required in the application of repeated coats of varnish, the time and labor expended, and the storage-space 35 occupied by the objects under treatment are all sources of expense almost completely obviated by our invention, which consists in a japan or other body varnish prepared in a sheet of the requisite thickness and of sufficient solidity to bear handling, the cutting of said sheet into 40 pieces of shape and dimensions adapted to the article to be covered, and the mode of covering surfaces with varnish by the application of said sheets to said surfaces and fixing them 45 there by means of heat or other proper agent.

That others may fully understand our invention, we will more particularly describe it, having reference to the accompanying drawings, wherein—

Figure 1 is a perspective of a water-hook 50 made in accordance with our invention. Fig. 2 is a central section of the same. Fig. 3 represents a rosette with the ground for the initial laid in by our invention. Fig. 4 represents a knife-handle japanned by our method. Fig. 5 55 is a perspective of a water-hook showing imitation stitches in japan. Fig. 6 is an ornament designed to illustrate the imitation of inlaid work or marquetry.

The japan or other body varnish is compounded in the usual way, only much less fluid than usual, and may be made into sheets by spreading it upon proper surfaces with any proper appliances—such as rollers, &c.—and permitting it to solidify by cooling or evaporation until it attains a proper consistency for convenient handling in sheets. It may then be removed and stored for immediate or future use.

In the drawings, A represents the exposed 70 metallic surfaces, and B indicates the japan-covered surfaces.

In Figs. 1, 2, 3, and 4 the japan is placed in portions of the surface which are depressed, and said depressions are filled up with the varnish. 75

By the ordinary methods heretofore practiced the japan would be applied in one of three ways: first, with a brush in repeated layers; second, by dipping and carefully wiping off the portions to be left uncovered; third, 80 by dipping and subsequently grinding away the superfluous varnish after baking. These methods involve much time and labor, which is entirely obviated by our method.

When the varnish sheet is to be used it is 85 cut with knives or scissors into pieces suitable to cover the desired surfaces, and after being laid thereon the article may be subjected to heat to soften the sheet and cause it to settle upon and adhere to said surface.

Sometimes it may be desirable to cover the surface first with a coating of liquid varnish to insure greater tenacity of adhesion, when moderate heat only can be subsequently applied, and the delicacy of the object to be treated may be such as to preclude the subsequent application of heat and make it necessary to obtain the proper adhesion by means of cement 95

applied in a liquid form. In any case the principal object of our invention—viz., the application of the entire thickness of varnish at a single operation—will be accomplished.

5 In Fig. 3, at B', the japan sheet-blank is shown detached, and at B the same is shown after application to the boss or rosette.

As a rule greater strength and hardness of body can be attained by the application of heat, 10 and for that reason metallic articles are usually baked in an oven after varnishing.

It will be observed that varnish may in this 15 way be applied in different colors, forming geometrical or other figures, imitating marquetry, &c. Such an application is shown in Fig. 6, and is designed to represent portions *d e f g h* of the design in different-colored varnishes, cut out and united in the usual way in inlaying.

The edges of the several contiguous pieces are 20 softened and united by the heat of the oven.

It will be observed, also, that varnish applied in sheets, as by our method, is capable of receiving and retaining the impression of tools during the subsequent treatment. Such 25 a result is shown in Fig. 5, where parts of the surface have been traversed by a toothed wheel in imitation of stitches, as at I.

Articles coated with sheet-varnish, as herein described, are easily distinguishable from 30 similar articles coated by dipping or by the brush, by the plainly-distinguishable edges of

the coating-sheet, and by a general character of smoothness and body of surface, due to the greater thickness and homogeneity of the coating applied in a single sheet and derived from its being subjected to only one baking. This 35 characteristic appearance is palpable to the experienced eye, but is difficult to formulate in words.

Having described our invention, what we 40 claim to be new is—

1. Japan or other body varnish prepared in solid form in sheets of such thickness as may be desired, adapted to be applied to the surfaces to be covered, whereby the entire thickness or body of varnish may be applied at a 45 single operation.

2. The mode or method of applying japan or other body varnish, which consists, essentially, in applying a solidified sheet of varnish having the required thickness or body to the surface to be protected, and causing the same to 50 adhere by means of heat.

3. Metallic articles the surfaces whereof are to the desired extent covered with sheets of 55 japan varnish made adherent by means of heat.

EDWIN R. CAHOONE.
